UNITED STATES PATENT OFFICE.

JOHN D. HODGE, OF KEARNY, NEW JERSEY.

BENCH-REST FOR VISE-WORK.

SPECIFICATION forming part of Letters Patent No. 630,698, dated August 8, 1899.

Application filed October 29, 1898. Serial No. 694,901. (No model.)

To all whom it may concern:

Be it known that I, JOHN D. HODGE, a citizen of the United States, residing at Kearny, in the county of Hudson and State of New Jersey, have invented certain new and useful Improvements in Bench-Rests for Vise-Work, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention is intended for the use of machinists, carpenters, pipe-fitters, &c., and is adapted to be applied to a work-bench and employed in connection with a vise or the like to support the rearwardly-projecting free end of a piece of work. The objects of the invention are to hold said free end of a piece of work in place and sustain its weight, so that the piece of work will not be bent or broken or dislodged from the vise or other tool in which it is held for working; to provide a support or rest which can be attached at any point along the length of the bench and which is also capable of vertical and angular adjustment; to provide means for making said vertical adjustments with exactness and ease even though a heavy weight is being supported; to obtain a compact, convenient, and durable construction, and to secure other advantages and results, some of which may be referred to hereinafter in connection with the description of the working parts.

The invention consists in the improved bench-rest for vise-work, &c., herein described and in the arrangements and combinations of parts of the same, all substantially as will be hereinafter set forth and finally embraced in the clauses of the claim.

Referring to the accompanying drawings, in which like letters of reference indicate corresponding parts in each of the several views, Figure 1 is a side view of the bench-rest entire, and Fig. 2 is a front view of the same. Fig. 3 is an enlarged sectional view on line *x*, Fig. 1, showing more especially the relations of a certain post to the supporting clamp and other parts. Fig. 4 is a section on line *y*, Fig. 3, showing a certain collar; and

Fig. 5 is a central longitudinal section of the socketed end of a wrench used in operating the rest, together with the stud receiving said wrench.

In said drawings, *a* indicates a clamp adapted to be secured to the edge of the work-bench and having an upright portion *a'*, adapted to come in contact with the edge of the bench, and arms *a²* *a³*, projecting therefrom at right angles to lie above and below the bench top, parallel thereto, as is common in clamps. Said lower arm *a³* is perforated and threaded to receive a set-screw *b* of any usual construction, its upper end engaging the under surface of the bench top, so that the clamp *a* may be firmly fixed thereon in the ordinary way. The upright part *a'* of the clamp is perforated, as at *c*, to receive a post *d*, adapted to be inserted in place from the rear and extend horizontally forward from the clamp *a*, as shown. The rear end of said post is provided with a head *d'*, which lies in a recess *c'* at the back of the upright part *a'* and prevents forward withdrawal of the post. Said post *d* is centrally and longitudinally slotted for a portion of its length forward of the clamp *a*, as shown at *e*, said slot being adapted to receive the upright *f'* of a support *f*. The support *f* comprises the upright *f'* and a head-piece *g*, having a socket *g'*, into which the upper end of the upright *f'* fits. The piece of work to be supported rests upon said head-piece *g*, and by having said head-piece detachable different forms of head-pieces adapted to different kinds of work may be used.

The upright *f'* is of any desired length and is preferably rectangular in cross-section and fitted to slide freely in the slot *e* without undue looseness in the direction of the width of said slot. To enable said upright to be set and held at any desired height, I have provided the set-screw *h*. The forward end of the post *d* is centrally and longitudinally bored, as at *d²*, inward to the slot *e*, and threaded to receive said set-screw *h*.

To prevent the end of the set-screw *h* from directly engaging the upright *f'* and thus injuring or defacing the side of said upright, a thrust-piece *i* is inserted therebetween. Said thrust-piece fits loosely in the slot *e* and is held from dropping out by a head *i'* at one end and a pin *j* at the other.

A collar or washer *k* may be placed upon the post *d* between the upright *f'* and the front face of the clamp *a*, if desired, so that said upright will not directly engage said front face.

In operating my bench-rest it is first secured by the clamp *a* to the bench at the point best suited to the work in hand, it being understood that when not in actual use 5 the device is removed and kept under the bench or in any other convenient place. An appropriate head-piece having been placed upon the upright *f'* the set-screw *h* is loosened and the support *f* is raised or lowered 10 to the proper height. Then by tightening the set-screw *h* the upright *f'* is gripped between the washer *k* and thrust-piece *i*, the head *d'* of the post *d* being at the same time drawn firmly into its seat. Said post *d*, with its 15 head *d'*, is preferably made cylindrical and the perforations *c* and recess *c'* therefor circular, so as to permit, when the set-screw *h* is loosened and vertical adjustment being made, of an angular adjustment also by a turning 20 of the post *d* upon its longitudinal axis.

In some kinds of work a more or less nice and accurate vertical adjustment of the support *f* may be necessary while a considerable weight is upon said support—as, for instance, 25 in leveling up a heavy piece of work—and to provide for a more exact and convenient movement of the upright *f'* than would be possible by hand in such cases I may cut upon one side of said upright *f'* teeth *l*, forming a rack, and provide a pinion *m* to intermesh therewith. Said pinion is preferably made removable, so that the upright can be more freely operated by hand, if desired, and I therefore form or attach the said pinion on 30 the end of the crank *n*, employed to turn the pinion, as clearly shown in Fig. 5. The end of the crank *n* is also socketed, as at *n'*, to receive a stud *o*, upon which the crank turns. At the opposite side of the upright *f'* from 35 the pinion *m* is a friction-roller *p* to prevent the upright from moving away from the pinion, so that the teeth no longer engage. The studs *p'* and *o* of the friction-roller and pinion project from ears or extensions *k' k* upon 40 the collar *k*, which is loose upon the post *d*, and thus retain their proper position relative to the upright *f'* at whatever angle the latter is inclined.

Having thus described the invention, what 45 I claim as new is—

1. A bench-rest comprising a clamp for attachment to the bench, a slotted post extending outward from said clamp and turning axially in its bearings therein without longitudinal movement, a support having an upright extending transversely through said slotted post, and means for forcing said upright longitudinally of said slot against the clamp to lock said upright and post, substantially as set forth.

2. A bench-rest comprising a clamp having a perforated body portion, a slotted post

having its end lying in said perforation and provided with a head preventing withdrawal while permitting rotary movement, a support 70 having its upright sliding in said slot, and a set-screw working longitudinally in the end of the post to force said upright toward the clamp, substantially as set forth.

3. In a bench-rest, the combination with 75 perforated means for attachment to a bench, of a forwardly-projecting post having its end lying in said perforation and provided with a head preventing withdrawal, said post being longitudinally slotted intermediate of the 80 ends, a support sliding in said slot, a washer surrounding the post on one side of said support and a thrust-piece inserted in the slot on the other side, and a set-screw working 85 axially in the forward free end of the post and extending into the said slot, substantially as set forth.

4. In a bench-rest, the combination with means for attachment to a bench, said means providing an upright part perforated and recessed, of a forwardly-projecting post capable of turning in said perforation and having a head lying in said recess preventing withdrawal, said post having a slot intermediate of its two ends and being axially bored out 95 and threaded from the free end into said slot, a support having its upright part sliding in said slot, and a set-screw inserted in the free end of the post and being adapted to force 100 said support toward said upright part and seat the head of the post firmly in the recess, substantially as set forth.

5. A bench-rest comprising means for attachment to a bench, a forwardly-projecting post capable of longitudinal and rotary movement, a support having its upright sliding in an opening in said post and having teeth formed on one side, a pinion intermeshing with the said teeth, means for turning said pinion to raise or lower the support, and means for 105 clamping said support and said post against movement, substantially as set forth.

6. In a bench-rest, the combination of a clamp to be secured to the bench and having its body portion perforated, a post having its 110 end lying in said perforation and provided with a head to prevent withdrawal, a support having an upright sliding in an aperture in said post, a collar arranged on the post, a friction-roller and a pinion disposed at opposite sides of the upright on studs projecting from said collar, said pinion engaging co-operating rack-teeth on the upright, means for rotating said pinion, and a set-screw which simultaneously holds said collar, support and 115 post against movement, substantially as set forth.

7. In a bench-rest, the combination with means for attachment to a bench, of a horizontally-projecting post having a transverse aperture, a set-screw extending axially from the free end of said post into said aperture, a support having its upright portion extending through said aperture and toothed on one

side, a removable pinion intermeshing with said toothed upright, an opposite friction-roller, and means for turning said pinion, substantially as set forth.

5. 8. A bench-rest comprising means for attachment to a bench, a horizontally-projecting post adapted to turn in its bearings and having an aperture, a collar arranged on said post, a support extending through the aperture in the post and provided with rack-teeth, and a pinion and friction-roller arranged at opposite sides of the support and pivoted on studs projecting from the said collar whereby they retain their proper relative position to 15 the support as the post is oscillated, substantially as set forth.

9. In a bench-rest the combination of a clamp for fastening the device to a bench, a post outwardly projecting from said clamp, 20 a support having its upright portion extending through an opening in said post and provided with rack-teeth, a removable handle or

crank having a socketed end and a pinion thereon adapted to coöperate with said rack, and a stud receiving the socketed end of said 25 crank, substantially as set forth.

10. In a bench-rest, the combination with means of attachment to a bench, said means providing a perforation for receiving the end of a post, of said post, projecting outwardly 30 from the bench and being capable of turning in said perforation and having a transverse aperture, a support having its leg sliding in said aperture, and means for clamping said leg against movement and said post against 35 turning, substantially as set forth.

In testimony that I claim the foregoing I have hereunto set my hand this 27th day of October, 1898.

JOHN D. HODGE.
